BASKET

Henry S. Johns, Cleveland Heights, Ohio

Application April 17, 1944, Serial No. 531,397

5 Claims. (Cl. 217—122)

1

This invention relates to baskets and, while certain features of construction employed in the same may be utilized for manufacturing baskets of other materials, the invention has for its principal object to enable baskets to be made from veneer or other thin sheet-like material in such manner as to render them capable of speedy and cheap production while possessing unusual qualities of strength and rigidity. Further and more limited objects of the invention will be pointed out hereinafter in connection with the description of the drawings and will be realized in and through the combinations of elements embodied in the claims hereof.

Referring to the accompanying drawings, Fig. 1 represents a side elevational view of a basket constructed in accordance with my invention; Fig. 2 a plan view of the aforesaid basket; Figs. 3 and 4 are details in section corresponding respectively to the lines 3—3 and 4—4 of Fig. 1; Figs. 5, 5^a and 5^b are details in section, the sections being taken intermediate of the loops, and showing modifications of the manner of securing together the side and end elements and the bottoms of baskets of the type shown in the preceding views; Figs. 6 and 7 are views, similar respectively to Figs. 1 and 2, showing a modified form of my invention; Figs. 8 and 9 are details in section corresponding respectively to lines 8—8 and 9—9 of Fig. 6; and Fig. 10 is a detail in perspective of the lower portion of one of the sides of the basket handle shown in Figs. 6 and 7.

Describing by reference characters the parts shown herein and referring first to Figs. 1 to 4, inclusive, 110 denotes the bottom of a basket of a familiar six-quart type, such as used for the packaging of fruit and vegetables. This bottom is made of thin sheet-like material, such as veneer, which may be about one-tenth inch in thickness, and is provided with outwardly convex ends 110^a connected by parallel sides 110^b. The side and end panels of the basket are made from six pieces of thin sheet-like material, such as veneer, identical in shape and dimensions, thereby reducing the number of operations necessary for the production of the basket. As will appear from Figs. 1 and 2, each side panel 111 and each end panel 118 is rectangular in shape and the side panels are spaced apart midway of the length of the basket to provide a vertical slot 121 between adjacent side edges of said panels. The upper ends of the side panels are secured, as by staples 13, to and between inner and outer upper reinforcing bands 114 and 115. The lower

2

ends of the side panels are also secured to and between lower reinforcing bands 116 and 117. It will be noted that these bands are of such length that they overlap, as shown at 114^a and 115^a, thereby enabling the overlapping portions to be firmly secured together by means of the staples, the reinforcement thus providing insuring strength at the discontinuous end portions of the bands.

10 118 denotes the end panels of the basket, the same having their upper ends secured to and between the reinforcing bands 114 and 115 and their lower ends secured to and between the reinforcing bands 116 and 117. In practice, the 15 edges of the end panels will occupy an overlapping relation with respect to the proximate edges of the respective side panels 111 adjacent thereto. For convenience of machine-stapling the side and end panels together and to the reinforcing bands, and assuming that the basket is moved 20 counterclockwise with respect to the stapling means, the edges of the left hand end panel 118 will overlap the adjacent edge of the side panel 111 and the edge of the other side panel 111 will overlap the adjacent edge of the other end panel 118, and this successive overlapping arrangement 25 will extend around the other side of the basket. However, it is immaterial, so far as strength is concerned, whether the end and side panels be 30 overlapped in this manner. The overlapping, however, imparts strength to the joints formed between the end and side panels.

The bottom is secured in place by means of wide wire loops, each comprising legs 119 extending 35 along the upper surfaces of the side portions of the bottom and preferably along the upper surfaces of the end portions thereof, and being secured to the bottom by having their ends projected through the bottom and bent upwardly into 40 engagement therewith, as shown at 119^a. The outer looped ends 119^b are bent downwardly between the inner reinforcing band 116 and the lower end of the appropriate side panel 111 or end panel 118 and are secured to the lower reinforcing 45 bands and to the lower ends of the panels by means of staples 120, which preferably engage the upper surfaces of the end-closures of the loops. The loops hold the bottoms of the panels tightly and securely against the edge of the bottom. The 50 staple fasteners 13 and 120 are spaced apart midway of the lengths of the side panels to provide vertical spaces along the said panels and between the same and the outer reinforcing bands for the passage of the sides of the handle.

55 Reference has been made hereinbefore to the

fact that the side panels are spaced apart for the purpose of providing opposed vertical slots 121 therebetween. These opposed slots are for the purpose of receiving the lower end portions 19^a of the sides of a handle, the upper arched portion of which is shown at 19. The lower portions of the handle sides are of substantially the same width as the slots 121 and each such portion has a reduced lower end or tongue 19^b which is narrower in width than the portion thereabove, for a purpose to be explained hereinafter.

The handles are detachably secured in place by means of resilient tongues struck therefrom and adapted to engage beneath one or both of the upper reinforcing bands. As shown herein, each handle is provided with a pair of outwardly projecting tongues 19^d, struck therefrom, the tops of which are adapted to engage beneath the outer reinforcing band 115, and with an inwardly projecting tongue 19^e which is adapted to engage beneath the inner reinforcing band 114. For the purpose of securing the lower ends of the handle in place, I employ loops having legs 122 resting on the top of the bottom and having their ends projected through and fastened to and beneath the bottom, as shown at 123, the looped ends 123^a projecting outwardly above the lower reinforcing bands and each receiving the lower reduced end or tongue 19^b of the handle, the shoulders 19^c resting on the sides of the loops. The shoulders 19^c prevent the sides of the handle from being pushed downwardly further than is necessary to enable the tongues thereon to be inserted between their respective lower reinforcing bands. The shoulders 19^c and the tongues 19^d and 19^e are so arranged that when the tongues are engaged beneath their respective bands, the shoulders will be in engagement with the legs 122 of the loops, thus preventing the sides of the handle from being pushed downwardly further than necessary to enable the tongues 19^d and 19^e thereon to engage the bottoms of their respective reinforcing bands whereby a rigid as well as detachable connection is obtained between the handle and the basket proper. The resiliency of the upper reinforcing bands permits the tongues 19^d and 19^e to pass therebetween when the handle is inserted into and removed from the basket proper.

When the parts of which the basket is formed are assembled, the handle constitutes a central reinforcement for the sides of the basket. Furthermore, the fact that it is readily removable from the basket enables the baskets themselves to be nested for shipping, separate from the handles, thereby economizing greatly in shipping space. Still further, where the material of which the baskets are made is incompletely dried or seasoned, the nesting of the baskets enables them to retain their shape. Furthermore, the nesting of the baskets in shipment insures their delivery in a clean condition. The fact that the baskets retain their shape enables the handles to be fitted properly in the vertical slots provided therefor and also enables the covers to be conveniently applied to and fitted upon the tops of the baskets after the latter shall have been filled.

The manner in which the handles are secured in place enables the weight of the basket and its contents to be supported from the upper reinforcing bands; and the manner in which the bottom is united to the sides and ends forms a particularly strong connection between these parts and the reinforcing bands.

It is also within the scope of my invention to utilize the loops which receive the reduced ends of

the sides of the handle as the means for securing the bottom in place and without utilizing the additional loops shown and described herein. It is believed that this will serve the purpose of enabling the bottom of the basket to be supported by the inner reinforcing band which, as shown, is stapled to the outer reinforcing band.

While the loops are particularly desirable in connection with basket bottoms wherein the grain runs lengthwise of such bottoms, they are also desirable for use in baskets wherein the grain of the bottoms runs crosswise thereof.

In Fig. 5 I have shown a modification of the invention wherein the bottoms of the side panels 111 and end panels 119 are shown as fastened to the bottom 130 by being creased above their respective bottoms and bent inwardly beneath the bottom 130 and stapled thereto, as shown at 131. In this construction, no inner lower reinforcing band is provided, the outer reinforcing band 132 being fastened to the end and side panels above the bottom 130. The tops of the side and end panels are secured to and between upper and lower reinforcing bands, indicated at 133 and 134.

In Fig. 5^a there is shown a further modification of the means for securing the basket bottom to the bottoms of the side and end panels. In this view, the ends and sides of the bottom 135 are bent downwardly at their edges, thereby to provide a flange 136, the bottom of which registers with the bottoms of the sides and ends and which is secured to the outer lower reinforcing band 117 and to the bottoms of the sides and ends by the staples 120.

In Fig. 5^b there is shown a still further modification wherein the sides and ends of the bottom 137 are bent upwardly at their edges thereby to provide an upwardly projecting flange 138, which is secured to the outer lower reinforcing band 117 and to the bottoms of the sides and ends of the basket by staples 120. In this view, the bottom of the basket registers with the bottoms of the sides and ends and the bottom of the reinforcing band 117.

In Figs. 6, 7, 8, 9 and 10, there is shown a modification of my invention wherein instead of using six panels, of identical dimensions, I employ only two side panels and two end panels, the side panels being identical as to dimensions and the end panels being identical as to their dimensions but of less width than the side panels.

In these views, 210 denotes the bottom of the basket, 211 the side panels and 212 the end panels. The edges of the end panels overlap, and are overlapped by the adjacent edges of the side panels in the same manner as is the case with the preceding embodiment of my invention, and the tops of the side and end panels are inserted between an inner reinforcing band 214 and an outer reinforcing band 215 and secured thereto by staples 113 and the bottoms of the side and end panels are inserted between an inner reinforcing band 216 and an outer reinforcing band 217 and secured thereto by staples 220. The upper bands are of such length as to overlap, as shown at 214^a and 215^a and the lower reinforcing bands also overlap in like manner as indicated at 216^a in Fig. 9, thereby enabling the overlapping portions to be secured firmly together by means of the staples, the reinforcement thus provided insuring strength at the discontinuous end portions of the bands. The bottom is secured to the sides by means of wide wire loops each comprising legs 219 extending along the upper portions of the side portions of the bottom 210 and being secured thereto by having their ends

projected through the bottom and bent upwardly into engagement therewith as shown at 219^a. The outer looped ends 219^b are bent downwardly between the inner reinforcing band 216 and the lower end of the appropriate side panel 211 and are secured to the lower reinforcing bands and to the lower ends of the side panels by means of the staples 220 which preferably engage the upper surfaces of the closed ends of the loops. In practice, the bottoms are made of dry veneer and the panels and reinforcing bands are made of wet veneer and, during the shrinkage which occurs, due to "seasoning," the bands will draw the bottoms of the panels, and particularly the bottoms of the end panels, tightly against the bottom, which makes it unnecessary, where the bottoms and panels are made of the material specified, to employ wire loops such as the loops 219—219^b for the purpose of obtaining proper contact between the bottoms of the end panels and the basket bottom.

221 denotes the upper or arched portion of a handle, the sides 221^a of which are inserted between the outer upper and lower reinforcing bands 215 and 217 and the outer surfaces of the respective side panels, midway of the length of the basket, it being noted that the fasteners 113 and 220 are spaced apart midway of the lengths of the side panels thereby to provide vertical spaces along such panels and between the same and the outer reinforcing bands for the passage of the sides of the handle. The lower end of each side of the handle is provided with a centrally arranged tongue 221^b, there being shoulders 221^c provided on opposite sides of each tongue where it is joined with the bottom of the side of the handle. The loops 219—219^b which are nearest to the centers of the sides of the bottom are located close to the tongues 221^b whereby the staples 220 will cause the portion of the outer reinforcing band therebetween to assume an outwardly curved shape when the tongues are inserted in place, the curvature being sufficient to insure that the shoulders 221^c will engage the top of the band, as shown in Fig. 6, thus preventing the sides of the handle from being pushed downwardly farther than is necessary to enable the tongues thereon to engage the bottom of the upper outer reinforcing band. It will be noted that the sides of the handle are provided each with an outwardly projecting tongue 221^d struck therefrom, and this tongue is so located with respect to the shoulders 221^c that, when the shoulders are in engagement with the lower outer reinforcing band, the top of the tongue 221^d will be engaged with the bottom of the outer upper reinforcing band. This insures a rigid as well as a detachable connection between the handle and the basket proper. The resiliency of the upper reinforcing bands permits the tongues 221^d to pass between the outer of said bands and the side panels when the handle is inserted into and removed from the basket proper.

While the handles may be inserted between the inner surfaces of the side panels and the inner reinforcing bands, in which case the tongues 221^d would project inwardly from the sides of the handle, it is preferable to place the sides of the handles on the outside, as shown and described, whereby injury to fruit in the basket by the handles will be prevented.

Due to the manner in which baskets made in accordance with my invention are constructed, I am able to provide them with sufficient strength and rigidity to enable them to withstand all incidents of ordinary use to which they are subjected

and at the same time to employ thin material, such as veneer, fibre board, sheet plastic, cardboard, pressed ground wood or other suitable material for all of the parts thereof. In making six-quart baskets of veneer, I have employed, for the side and end panels and reinforcing bands, veneer of a thickness of approximately $\frac{1}{8}$ " and, for the handles, veneer of a thickness of approximately $\frac{1}{8}$ ". Where materials other than veneer are used, the thickness of such materials will necessarily vary in accordance with the strength thereof.

This application is a continuation in part of my copending application Serial No. 493,525, filed July 5, 1943, which has matured into Patent No. 2,240,882, issued May 20, 1947.

Having thus described my invention, what I claim is:

1. A basket comprising a bottom and side and end panels made of relatively thin and light material, an outer upper reinforcing band within which the upper ends of the side and end panels are secured, an outer lower reinforcing band to and within which the lower ends of the side and end panels are secured, and means for securing the basket bottom within the bottom portions of the side and end panels, and an inverted U-shaped handle the sides whereof are insertable between the outer upper reinforcing band and the outer surfaces of the side panels and having at their lower ends tongues adapted to be inserted within the lower reinforcing band and having shoulders above said tongues adapted to engage the lower reinforcing band, the sides of the handle each having an integral resilient projection adapted to permit the insertion of the sides of the handles between the upper reinforcing band and the external surfaces of the side panels adjacent to said band and being so located as to engage the lower edge of the said upper reinforcing band when the shoulders therebelow engage the upper edge of the lower reinforcing band.

2. A basket comprising a bottom and side and end panels made of relatively thin and light material, a vertical slot being provided at the central portion of each side of the basket between the panels on such side, inner and outer upper reinforcing bands to and between which the upper ends of the side and end panels are secured, an outer lower reinforcing band to and within which the lower ends of the side and end panels are secured, and means for securing the basket bottom within the bottom portions of the side and end panels, an inverted U-shaped handle the lower portions of the sides whereof are insertable into the vertical slots and between the inner and outer upper reinforcing bands and within the lower reinforcing band, the bottoms of the sides of the handle being reduced to form tongues with shoulders thereabove, loops secured to the basket bottom and extending outwardly into the said slots and above the lower reinforcing band and adapted to receive the said tongues and to engage said shoulders, and one or more projections on each of the sides of the handle in position to engage the lower edge of an upper reinforcing band when the tongues on the lower ends of the handle sides are positioned within said loops.

3. A basket comprising a bottom and side and end panels made of relatively thin and light material, a vertical slot being provided at the central portion of each side of the basket between the panels on such side, inner and outer upper reinforcing bands to and between which the up-

per ends of the side and end panels are secured, inner and outer lower reinforcing bands to and between which the lower ends of the side and end panels are secured, an inverted U-shaped handle the lower portions of the sides whereof are insertable into the vertical slots and between the inner and outer upper reinforcing bands and between the inner and outer lower reinforcing bands, the bottoms of the sides of the handle being reduced to form tongues with shoulders thereabove, loops secured to the basket bottom and extending outwardly into the said slots and above the lower reinforcing bands and adapted to receive the said tongues and to engage said shoulders, one or more projections on each of the sides of the handle in position to engage the lower edge of an upper reinforcing band when the tongues on the lower ends of the handle sides are positioned within said loops, and fasteners securing the tops and bottoms of the panels to the top and bottom reinforcing bands respectively.

4. A basket comprising side and end panels made of relatively light and thin material, inner and outer upper reinforcing bands and inner and outer lower reinforcing bands extending around and secured respectively to the upper and lower ends of said panels, a bottom within the lower portions of the said panels and having its outer edge portions adapted to engage and be supported by the lower inner reinforcing band, loops secured to opposite sides of the bottom substantially midway between the ends thereof and having their looped ends extending beyond the side edges of the bottom, an inverted U-shaped handle, the sides whereof are insertable between the upper reinforcing bands and having each a tongue at its lower end adapted to be inserted within the outer end of one of said loops and between the lower reinforcing bands and each having shoulders above said tongue adapted to engage the projecting sides of one of said loops, and means carried by the handle sides for detachably engaging one of the upper reinforcing bands.

5. A basket comprising a bottom and side and end panels made of relatively thin and light material, a vertical slot being provided at the central portion of each side of the basket between the panels on such side, inner and outer upper

reinforcing bands to and between which the upper ends of the side and end panels are secured, means for securing the basket bottom within the bottom portions of the side and end panels, and an inverted U-shaped handle the lower portions of the sides whereof are insertable into the vertical slots and between the inner and outer upper reinforcing bands, said inverted U-shaped handle having a plurality of projections formed on each of the sides of the handle and being extended therefrom to engage the lower edges of the inner and outer upper reinforcing bands, at least one of said projections on each side of the handle being extended therefrom in an opposite direction to another projection formed on the same side of the handle, said projections being exposed when said handle is assembled in the basket whereby the projections can be manually forced inwardly of said handle to lie substantially in the plane thereof and permit the removal of the handle from association with the basket.
